UNITED STATES PATENT OFFICE.

HANS R. RALL, OF CHICAGO, ILLINOIS.

RAILWAY SWITCH.

1,407,219.

Specification of Letters Patent. Patented Feb. 21, 1922.

Application filed August 27, 1921. Serial No. 496,097.

To all whom it may concern:

Be it known that I, HANS R. RALL, a citizen of the United States, residing in Chicago, in the county of Cook and State 5 of Illinois, have invented certain new and useful Improvements in Railway Switches, of which the following is a specification.

This invention relates to that class of railway switches or crossings having a 10 switch rod provided with means for adjustably connecting it with the rails.

The principal object of the invention is to provide a simple, economical and efficient railway switch having a switch rod and 15 movable rail members, and having an improved, simple, strong and efficient means for adjustably connecting the switch rod with the movable rail members, and for securely connecting the movable rails in adjustable relation to each other and in properly spaced apart position with respect to 20 each other and with respect to the fixed or stationary rails of the switch or crossing.

Other and further objects of the invention 25 will appear from the following description and claims, and from the accompanying drawings, which are made a part hereof.

The invention consists in the features, 30 combinations, and details of construction and arrangement of parts herein described and claimed.

In the accompanying drawings—

Figure 1 is a plan view of a railway switch having a switch rod and movable 35 rail members provided with means for connecting the same in adjustable relation constructed and adapted to operate in accordance with my invention;

Fig. 2 is an enlarged detail view in trans- 40 verse vertical section taken on line 2—2 of Fig. 1, looking in the direction indicated by the arrows, and showing the track rails on one side of the track and switch in section, and the switch rod and my improved con- 45 necting means forming an adjustable connection between the switch rod and movable track rail or switch rail in side elevation, the connecting means on both sides of the switch or track being identical;

Fig. 3 is a plan view of my improved adjustable connecting mechanism shown in 50 Figs. 1 and 2;

Fig. 4, is a view in elevation showing my improved adjustable connecting mechanism 55 in operative position and forming a connection between the switch rod, which is

shown in transverse section, taken on line 4—4 of Fig. 1, looking in the direction indicated by the arrows;

Fig. 5 is a detail plan view of a toothed or serrated and perforated portion of a switch rod shown in Figs. 1, 2, 3 and 4;

Fig. 6, is a view in side elevation of the serrated switch-rod shown in Fig. 5; and

Fig. 7 is a detail view of a toothed or serrated detent or rod-engaging toothed member shown in Figs. 3 and 4 in engagement with the switch rod.

In constructing a railway switch or crossing provided with a switch rod and movable 70 rails or rail members having means for adjustably connecting the switch rod and movable rails in accordance with my invention, I provide railway ties 1 on which are laid and secured fixed track rails 2, 2, in the usual or 75 any desired or ordinary manner. And movable or adjustable switch rails 3, 3, are laid adjacent to and in adjustable relation to the fixed rails and in position to be supported by the ties in any position into which 80 they are moved or adjusted. Tie plates 4 are rigidly secured to the ties by means of spikes or other ordinary or desired securing means, and are rigidly connected with the fixed or stationary track rails 2 in the usual 85 or any ordinary or suitable manner. The tie plates 4 extend inward between the main track rails, and beneath and in supporting engagement with the adjustable or movable switch rails 3 which rest upon and in slid- 90 able engagement with the top surfaces of the tie plates, the rail points 5 being adjustable or movable transversely of the track into and out of engagement with the main track rails 2 to open and close the switch. 95

The opposite extremities of the rails 3 are supported in operative position in the ordinary manner familiar and well known to those skilled in the art, and are therefore not shown in the drawings. 100

A switch rod 6 is adjustably or movably mounted between the ties in transverse relation to the track, and extends transversely beneath the main track rails 2 and the adjustable switch rails 3, and is connected with 105 an operating rod 7, which is adapted to be operatively connected with and operated by switch-operating lever mechanism, or any desired ordinary and well known or suitable form of switch-operating means. 110

At least one, and by preference, two socket members 8 are provided, each secured to the

inner side of a corresponding movable switch rail 3 by means of bolts 9 and nuts 10, which bolts extend through the upright portion 11 of the socket member or bracket 5 8 and through the upright web or body of the rail, or by similar or other suitable securing means.

Each socket member 8, thus secured in fixed relation to a corresponding one of a pair of parallel switch rails to be adjustably connected in operative position, and secured in parallel relation so as to be readily moved to switch-opening or switch closing position, and spread apart, or adjusted closer together 15 to properly spaced-apart position, is adapted to be adjustably connected with the transverse switch rod 3. And each of said socket members 8 comprises in its construction a laterally projecting approximately horizontal body portion or arm 12 which is adapted to rest upon the top surface of the inner base portion 13 of the corresponding movable switch rail 3 and projects inward toward the center of the track laterally beyond the inner side margin of the rail base, and has a depending main socket portion integral with the inner extremity of said arm 12 and adapted to project downward on the inside of the rail and below the level of the rail 20 base, and between the ties. This inner depending portion 16 of the socket member 8 is provided with a horizontal slot 17 which extends through the depending socket portion 16 below the level of the bottom or base 25 of the rail and in transverse relation to the track rails and said socket member. Said slot 17 is adapted to admit and slidably and adjustably engage the switch rod 6.

The depending slotted socket portion 16 40 extends beneath the base of the movable rail to which it is attached, and has a horizontal notch or slot 29 in the side toward the rail and into which the inner side edge of the corresponding rail base extends. The 45 space occupied by the device is thus minimized.

The switch rod has a toothed edge or marginal portion 18 which consists of or comprises any desired number of teeth on the 50 vertical longitudinal edge or surface 19 of the switch rod, each of said teeth being, by preference, vertical and adapted to face inward toward the inner extremity or vertical side wall 20 of the slot 17 in the socket member, when the switch rod is in operative position in adjustable engagement with the socket member and slot.

An intermediate laterally toothed angular bar member 21, provided with a series or 60 any desired number of vertical laterally projecting teeth 22 in the vertical longitudinal side face thereof, and projecting toward and in adjustable opposed relation and overlapping engagement with the opposed teeth 18 65 on the switch rod, is mounted in the slot 17

in the socket member 8 and between the toothed portion 18 of the switch rod, and the inner side wall or bottom 20 of the slot 17, and has outer angular end portions 23 which project from and are integral with 70 the opposite end portions of the toothed bar 21. These angular end portions 23 are in parallel relation and extend on opposite sides of the depending portion 16 of the socket member 8 and in snugly fitting engagement 75 with the side walls of the same, so that the toothed bar 21 thus interposed between the toothed portion 18 of the switch rod, and the inner wall 20 of the socket member is removably held in the socket or slotted portion 17 of the socket member, and in relatively adjustable toothed engagement with the opposed teeth 18 on the switch rod.

The switch rod is provided with an elongated slot 24 which extends vertically 85 through the switch rod and is elongated in a direction longitudinally of the same. And this slot has a vertical side wall 25 on the side toward the teeth 18 and in parallel or approximately parallel relation to the series 90 of teeth 18. And a bolt 26 having a head 27 is mounted in vertical position in suitable vertical openings in the depending slotted portion 16 of the socket member 8, and in position to extend vertically through the 95 slot 17 in said socket member and through the elongated slot 24 in the switch rod. The vertical peripheral face or side of the bolt is thus in engagement with the side wall 25 of the elongated slot 24 in the switch rod 100 on the side of the bolt which faces toward the opposed overlapping relatively adjustably locking teeth 18 on the switch rod and teeth 22 on the bar 21 fixed to the socket member. The vertical peripheral side or 105 face of the bolt is thus adapted to hold the opposed teeth 18, and 21 in locking engagement in any position into which they are adapted to be adjusted with respect to each other. And the opposed engaged teeth 18 110 and 21 and said bolt thus hold the switch rod in securely connected adjustable relation to the socket member or members 8. Each bolt 26 is provided with a nut 28 in threaded engagement with the threaded end thereof, or with other similar or suitable securing means for holding the bolt firmly in operative position in engagement with the socket member and switch rod.

The switch rod shown in the drawings is 120 provided with two serrated or toothed side marginal portions or edges 18; and two socket members 8, 8, are shown in Fig. 1, each fixed to a different one of a pair of movable switch rails 3, and each adjustably connected with a toothed portion of the same switch rod 6. The adjustably connected switch rod and socket members are thus adapted to connect the movable switch rails in properly spaced apart rela- 130

tion to each other, and permit the rails to be spread apart or adjusted closer together, as required, so that the movable switch rails are adapted to be moved with facility transversely of the track and to and from switch-opening and switch-closing position and into and out of contact with the fixed track rails as desired.

It is obvious that the switch rod and socket members thus adjustably connected are adapted to be used in connection with either a single slip switch, a double slip switch, or a movable point crossing. And the switch rod thus operatively connected with and forming an adjustable connection between parallel movable switch rails, is adapted to be operated by any ordinary and well known or suitable switch-operating means, or from a switch stand which may be of any desired or ordinary type.

I claim:

1. In a railway switch, the combination of a switch rod, a socket member adapted to be secured to one of a pair of movable switch rails to be operatively connected, said socket member having a slotted portion into which said switch rod extends, opposed teeth located between and fixed to adjacent surfaces of said switch rod and socket member respectively and in engagement with each other, a bolt mounted in the socket member and in engagement with the switch rod and acting to hold said opposed teeth in adjustable relation, said engaged teeth and bolt acting to hold the switch rod and socket member in adjustable relation, and means for securing the switch rod in operative engagement with the other one of said pair of switch rails.

2. In a railway switch, the combination of a switch rod, a socket member adapted to be secured to one of a pair of movable switch rails, said socket member having a slotted portion into which the switch rod extends, opposed teeth fixed to adjacent surfaces of said switch rod and socket member, respectively and in engagement with each other, a bolt mounted in the socket member and having a side face in engagement with the switch rod and facing toward and tending to hold said engaged teeth in engagement, said engaged teeth and said bolt co-acting to hold the switch rod and socket member in adjustable relation, and means for operatively connecting the switch rod with the other one of said pair of switch rails.

3. In a railway switch, the combination of a switch rod, a socket member adapted to be secured to one of a pair of movable switch rails, said socket member having a slotted portion into which the switch rod extends, opposed teeth located between and fixed to adjacent surfaces of said switch rod and socket member respectively, a bolt

mounted in the socket member and in adjustable relation to the switch rod, said bolt having a peripheral face in engagement with the switch rod and facing toward and acting to hold said opposed teeth in engagement and in relatively adjustable relation between the switch rod and socket member, said engaged teeth and said bolt acting to hold the switch rod and socket member in adjustable relation, and means for operatively connecting the switch rod with the other one of said pair of rails.

4. In a railway switch, the combination of a switch rod having a toothed marginal portion, a socket member adapted to be secured to one of a pair of movable switch rails, and having a slotted portion into which said toothed portion of the switch rod extends, an intermediate toothed member interposed between the socket member and the toothed portion of the switch rod and in toothed engagement with the latter, a bolt mounted in the socket member and having a peripheral side face in engagement with the switch rod and tending to hold the toothed marginal portion of the switch rod in toothed engagement with said intermediate toothed member, said engaged toothed members and said bolt acting to hold the switch rod in adjustable relation to and in operative engagement with the socket member, and means for operatively connecting the switch rod with the other one of said pair of rails.

5. In a railway switch, the combination of a switch rod having a toothed marginal portion, and provided with an elongated slot, a socket member adapted to be secured to one of a pair of movable switch rails, said socket member having a slotted portion into which said switch rod extends, an intermediate toothed bar removably mounted between the socket member and the toothed portion of the switch rod and in toothed engagement with the latter, a bolt mounted in the socket member and extending through the elongated slot in the toothed switch rod, and having a side face of said bolt in engagement with the slotted portion of the switch rod and facing toward and acting to hold said toothed marginal portion of the switch rod in toothed engagement with said intermediate toothed bar, said engaged toothed members and said bolt acting to hold the switch rod and said socket member together in adjustable relation, and means for operatively connecting the switch rod with the other one of said pair of switch rails.

6. In a railway switch, the combination of a switch rod, a pair of socket members each adapted to be secured to a corresponding one of a pair of movable switch rails to be operatively connected, each of said socket members having a depending socket portion extending beneath the base of the rail to

which such socket member is secured and having a slotted portion into which said switch rod extends, opposed teeth fixed to said slotted socket member and switch rod 5 respectively and in engagement with each other, a bolt mounted in the socket member and in engagement with the switch rod and acting to hold said toothed members in adjustable relation, and means for securing 10 each of said socket members to a corresponding movable switch rail.

7. In a railway switch, the combination of a switch rod having a toothed marginal portion and provided with an elongated 15 slot, a socket member adapted to be secured in fixed relation to one of a pair of movable switch rails to be operatively connected, said socket member having a depending slotted portion projecting beneath the bottom of 20 the rail and into which said switch rod extends, an intermediate toothed bar fixed to the slotted socket member and in toothed engagement with the toothed switch rod, an upright bolt mounted in the socket member 25 and extending through the elongated slot in the toothed switch rod, and having a side face of said bolt in engagement with the slotted portion of the switch rod and facing toward and acting to hold said toothed marginal portion of the switch rod in toothed engagement with said intermediate toothed member, said intermediate toothed member and said bolt co-acting to hold said switch rod and said socket member securely connected in adjustable relation, and a second socket member 30 connected with the other one of said pair of switch rails and adjustably connected with said switch rod.

justable relation, and means for operatively connecting the switch rod with the other one of said pair of rails.

8. In a railway switch, the combination of a switch rod having a toothed portion and provided with an elongated slot, a socket 40 member adapted to be secured to one of a pair of movable switch rails, said socket member having an opening into which said toothed switch rod extends, an intermediate toothed member mounted in fixed relation 45 to the socket member and in engagement with the toothed portion of said switch rod, a bolt mounted in the socket member and extending through the elongated slot in the toothed switch rod, and having a side face 50 of said bolt in engagement with the slotted portion of the switch rod and facing toward and acting to hold the toothed marginal portion of the switch rod in toothed engagement with said intermediate toothed member, said intermediate toothed member and said bolt co-acting to hold said switch rod and said socket member securely connected in adjustable relation, and a second socket member 55 connected with the other one of said pair of switch rails and adjustably connected with said switch rod.

Signed at Chicago, Cook County, Illinois, this 18th day of August, 1921.

HANS R. RALL.
